United States Patent Office.

FRIEDRICH VILLARD, OF MOUNT EATON, OHIO.

Letters Patent No. 61,582, dated January 29, 1867.

IMPROVEMENT IN CRUCIBLE TONGS.

The Schedule referred to in these Letters Patent and making part of the same.

TO ALL WHOM IT MAY CONCERN:

Be it known that I, FRIEDRICH VILLARD, of Mount Eaton, in the county of Wayne, and State of Ohio, have invented new and useful improvements in Crucible Tongs; and I do hereby declare the following to be a full, clear, and exact description thereof, reference being had to the annexed drawing, making part of this specification, in which—

Figure 1 is a perspective view of my improved crucible tongs closed upon a crucible; and

Figure 2 is a perspective view of the same opened to grasp a crucible.

A are bars of iron or steel long enough to permit the moulder to use the tongs without discomfort from the heat of the furnace, bent at each end into segments of circles, B C, nearly approaching semicircles, the length of the bars being perpendicular to the planes of the circles, of which the segments are parts. The segments B are hinged together at D, and the segments C are hinged together at E. The radius of the curve of the segments B is of a different length from the radius of the segments C, so that one pair of tongs may be used for many different-sized crucibles. The elasticity of the bars of the tongs, when compressed by the hand, will cramp the segments around a crucible with sufficient force to prevent it from slipping in the tongs when it may be canted for pouring at will.

Having thus fully described my improvement, what I claim therein as new, and desire to secure by Letters Patent, is—

The arrangement of the bars A, and hinged circular segments B and C, combined together to form one or more crucible tongs, substantially as described and set forth.

FRIEDRICH VILLARD.
